HOWARD JOSLYN AND CHESTER L. LYNCH, OF SEATTLE, WASHINGTON.

SELECTIVE SIGNAL-TRANSMITTING APPARATUS.

1,133,034.

Specification of Letters Patent. Patented Mar. 23, 1915.

Application filed August 4, 1909. Serial No. 511,247.

To all whom it may concern:

Be it known that we, HOWARD JOSLYN and CHESTER L. LYNCH, citizens of the United States, residing at Seattle, in the county of King and State of Washington, have invented certain new and useful Improvements in Selective Signal-Transmitting Apparatus, of which the following is a specification.

10 This invention relates to electric signals. The object of the invention is to provide an improved method and apparatus for the sending of electric signals which originate through the making and breaking of an electric circuit, or circuits, to individual receiving devices, and thence through automatic controllers a signal is selectively transmitted to its destination without interference with other signals being delivered from 20 the receiving devices.

With these and other ends in view, the invention consists in the novel construction, adaptation and combination of devices, as will be hereinafter described and claimed.

25 In the drawings, Figure 1 is an elevational view of apparatus embodying our invention with a diagram of the electrical connections therefor. Fig. 2 is a plan view of apparatus utilized in printing registers for recording signals and which coöperate with the present invention. Fig. 3 is a sectional view taken through 3—3 of Figs. 1 and 2. Fig. 4 is a perspective view of one of the controller magnets and associated 35 parts. Fig. 5, 6 and 7 are side elevations of apparatus illustrating in three stages of operation certain parts of the apparatus.

The reference characters *a*, *a'* and *b*, *b'* 40 represent conductors of two signal originating circuits by which signals may be transmitted from stations through the medium of instruments, such as keys 1 and 2. While but two of these circuits are illustrated it is to be understood that the number thereof is not thus limited. Embraced in 45 the respective circuits are magnets 3 and 4 which upon being energized from the respective instruments will influence the angle levers 3' and 4' by attracting the armatures provided thereon for individually engaging an arm 5 provided upon a rock-shaft 6.

Mounted upon rock-shaft 6 is a block 7 having pivotally connected thereto an arm 8 arranged for horizontal vibration and which arm is engaged by the thread of a screw 9 through the agency of a spring 10. Said screw is rotated by a gear-wheel 11 which is driven from a pinion 12 through a train of spring-impelled clock wheels, not shown. The arm 8 is provided with a finger 8' which is arranged, when being swung by said screw in the direction opposite to that indicated by the arrows in Figs. 2 and 3, to engage with the sloping underside of an element *c'*, which constitutes a terminal of the conducting wire *c*, and cause such element to be moved into contact with the terminal *d'* of the conducting wire *d*. Said terminals compose an electric switch *S'* which will hereinafter be designated as the master-switch. Upon the shaft of screw 9 is a wheel 13 carrying a stop-pin 13' which is engageable by a hook-shaped finger 8'' upon the arm 8 so that when the latter has, through the offices of said screw, arrived at the end of its travel the rotation of the screw will be discontinued and whereupon the entire apparatus is brought to rest.

Upon the shaft 14 of pinion 12 is a friction wheel 15 which, upon occasion, is associated with a sector-member 16 to impart a rotary motion thereto when the peripheral surface of the member is frictionally engaged with the wheel 15. Said sector-member is supported on a stud 17 of an arm 18 which is carried on a shaft 19 having a depending arm 20 that is arranged to be engaged by an arm 21 of shaft 6 when the same is tilted by the power produced through the magnets 3 or 4 when one or the other of them is energized in the completion of the appropriate signal originating circuit.

S represents a switch having contacts *e'* and *f'* and forming the terminals of circuit wires *e* and *f*, which circuit is normally incomplete. Switch *S* is closed by a pin 22 provided upon the member 16 encountering and pushing the switch-contact *f'* against the companion contact *e'* when such member is brought into couple with the wheel 15 through the instrumentality of either of the

magnets 3 or 4 acting through the afore-described connections. It must be understood, however, that the switch S is closed only by maintaining the member 16 in couple with the wheel 15 sufficiently long to afford time for said member to carry the pin 22 into engaged condition with the contact f'. The member 16 is loosely mounted upon its supporting stud 17 and is yieldingly held by 10 a spring, such as 23, in the position illustrated. A spring 24 is advantageously used to retain the arm 18 in position to have the member 16 disengaged from the wheel 15.

The aforescribed parts are substantially similar to devices heretofore employed in printing registers for recording signals. The operation thereof may be explained as follows: When either, or both, of the signal originating circuits a-a' or b-b' are made 15 operative for the transmission of signals, as by manipulating keys 1 or 2, then the respective magnets 3 or 4 are energized and cause the affected angle lever, 3' or 4', to swerve the arm 5 to rock the shaft 6 in such 20 manner that the arm 8 is raised from the screw 9 and also to release (by the disengagement of the stop-pin 18') the aforesaid train of clock-wheels which is then put in motion to rotate the screw 9 and also 25 the friction wheel 15. By the raising of the arm 8 from the screw a spring 25 acts to swerve the arm 8 in the direction of arrow (Figs. 2 and 3), and during which the then elevated arm 8 passes inoperatively above 30 the switch contact c'. Meanwhile the member 16 has been acted upon to cause the same to be engaged with the wheel 15 and, if the closure of the signal originating circuit, as a-a', is sufficiently prolonged the pin 22 35 will serve to close the switch S for the passage of a current through wires e-f. When the current through the said magnet, or magnets, is interrupted as, for example, between the successive actuations of an employed key, as 1, the member 16 is withdrawn by spring 24 from the friction-wheel 15 and the spring 10 restores the arm 8 into engagement with the screw 9 to thereby effect the swinging of arm 8 to wipe the 40 switch element c' of the master-switch S' to close the same. The arm 8 being urged onward by the screw to beyond the switch would ultimately be brought into position to have the hook 8'' of the arm 8 presented 45 in the path of the stop-pin 18' to cause the screw and the driving train of wheels to become motionless. Ordinarily, however, the intervals between the recurring actuations of an angle-lever 3' or 4' are insufficient to 50 allow the hook 8'' being put into service. It is to be noted that the switch S is operative only while said angle-levers are effective and that the master-switch S' is operative only when the angle-levers are inoperative.

65 In carrying out our invention, we employ

a signal indicating instrument, such as a bell 26, which is connected by a current wire g with a conductor h common to the terminals h' and h' of two switches, designated by S⁵ and S⁶, and by a wire k with the terminal k' of a switch S⁸, while the other terminal l'' of the latter is connected by branching wires l with the terminals l' and l' of switches S⁵ and S⁶ respectively. The last named switches are operated by electro-magnets 27 and 28 whose windings are respectively embraced by the signal originating circuits b-b' and a-a' and will consequently be made operative through the medium of the aforesaid keys 2 and 1 which, as stated, are selected in the signal stations. As shown, the armatures of these magnets are secured to movable elements 27' and 28' which are respectively provided with upwardly extending arms 29 and 30 terminating in laterally directed ends 29' and 30'.

31 represents a shaft journaled in standards 32. This shaft is arranged to be rotated in the direction indicated, by the provision of spring actuated clock-work, or, as illustrated, by a weight 33 suspended by a line 34 passing around a sheave 35 which is secured to the shaft. The rotation of the shaft is, however, regulated by electrically controlled devices which are best shown in Figs. 1 and 4. Such devices comprise two arms 36 and 37 extending radially from diametrically opposite sides of the shaft and at their ends have offsets 36' and 37' which are arranged to individually engage stops 38 and 39 formed as lugs projecting from the ends of a lever 40 when the same is in either of its two positions. These stops are disposed in different elevations and horizontally spaced relation with each other so as to be at a greater distance apart than the diameters of said offsets. The lever 40 is equipped with an armature 41 for electromagnets 42 which are in circuit including the wire f upon the one side and the joined wires m and n on the other side. Wire m is connected with the contact m' of a switch S' and the wire n with the contact n' of the switch S². The other contact o' of switch S' being connected by a branch wire o with wire e intermediate the switch S and an audible alarm device, such as a buzzer 50 and which in turn is connected by a wire p with the wire f so that whenever the circuit controlled by the switch S is completed (through a relatively long closure of a signal originating circuit by manipulating the actuating key 1 or 2 therefor) notice is given through the buzzer at the distributing station to the effect that a message or call is about to be transmitted from one of the signal stations.

The manner of utilizing and the functions of the aforementioned switch may be understood from a description of an embodiment

of the same with coöperating mechanism illustrated, and most particularly, in Figs. 5, 6 and 7. The contacts c'' and n' of switch S^2 are arranged to be engaged through a cam 43 upon shaft 31 and which cam also serves, in coöperation with a spring 44, to impart appropriate motion to a lever 45 whereon are affixed the contacts l'' and o' respectively of the switches S^3 and S^4 to cause these contacts to be coupled with the complementary fixed contacts k' and m' . To accomplish the desired and relative closures of the switches influenced thereby and as disclosed by the drawings, 15 said cam is of the wiper type with a peripheral surface 43' which is substantially spiral and extending from the cam-hub to the beak 43'' upon diametrically opposite sides. From the beak the cam is undercut to provide a recess 43'''. 46 and 47 are arms provided for the shaft 31 and respectively terminate in offset fingers 46' and 47' which are similarly disposed with respect to the cam and to the arms 36 and 37. The 25 arms 46 and 47 are so located upon the shaft that in revolving they will be in positions to respectively engage or hook over the fingers 29' and 30' of the arms 29 and 30 when the latter are in normal positions and corresponding with the unemployed conditions 30 of the movable elements 27' and 28' of the magnets 27 and 28.

Before any operation, switches S , S^2 , S^3 and S^4 are open, while the switch S' is closed. The relatively extended primary signal is transmitted or initiated by the closing of switch S , following which the current flows over line e , thence over two paths, one of which, the main path, is 35 through line o , switch S' and line m through magnet 42 to line f , and the other path in 40 shunt with the main path is through buzzer 50, line p , to line f . The flow of this current causes the attraction of the armature 40 and the shifting of the cam and switch blades from the position shown in Fig. 5 to the position shown in Fig. 6, which condition endures during the time of this relatively extended closure of switch S . When 45 this relatively extended closure of switch S ceases and switch S opens thereby taking the current off of magnet 42 and allowing the armature 40 to spring back under the action of retractile spring 49, the cam and 50 other portions of the mechanism change from the position shown in Fig. 6 to the position shown in Fig. 7 which is the first occasion of the opening of the switch S' , and this condition endures during the passage 55 of the main signal which follows the primary initial closure. This passage of the main signal is effected through the closure of switch S^3 ; S^3 having previous to this stage been open. That is to say, when the 60 instrument 1, for example, is actuated to

close circuit $a-a'$ a current flows therethrough to cause the magnet 28 to become operative and attract the armature 28' to close the switch S^a . Whereupon a current flows through wire g from the associated 70 battery, through signal bell 26, and the wire h through closed switch S^3 and thence by wire h to the referred to battery. At the completion of the main signal the switch S^4 75 is closed and the closing of the switch S^4 sends current through line e , the switch S^2 and the line $n-m$ to magnet 42 thereby causing the armature 40 of this magnet to be attracted, permitting the shaft 31 to make another half-turn, all of which 80 changes the cam and adjacent parts from the position shown in Fig. 7 to the original position shown in Fig. 5, where the switch S' is closed and the switches S , S^2 , S^3 and S^4 are all open. Assuming that a signal 85 is to be delivered over a signal originating circuit from the station wherein the key 1 is located; and, according to a predetermined code, the key is operated by an appropriate succession of movements to effect 90 the closures of the key switch of various lengths or intervals but always, as previously explained, with an initial closure sufficient to render the closure of the switch S . During such relatively extended initial 95 closure of the key-switch, a current is passing through the coils of the magnet 28 to energize the same and by attracting the armature of its movable element the arm 30 is drawn from its normal position, to occupy the position in which it is shown in dotted lines in Figs. 6 and 7 and is so maintained during the continuance of the initial closure of the key-switch. The other arm 29 with the armature carrying element 10 27' is meanwhile held by a retractile spring 48 away from the inoperative magnet 27. With the arms 29 and 30 occupying such positions the power of the current acting through the coils of magnets 42 attracts the 11 armature 41 to depress the lever 40 to withdraw the stop 39 from in front of the finger 37', as represented in Fig. 5, with a release of the latter, whereupon the shaft 31 is released and is turned, through the agency 12 of the weight 33, or an equivalent, until its rotation is interrupted by the finger 36' encountering the stop 38. In thus rotating, the shaft 31 carries the elements attached thereto from the positions that are represented in Fig. 5 to those that are shown in Fig. 6, that is to say, the arms 46 and 47 are swung over so that the finger 46' of the former will be to the rear of the finger 29' of arm 29 and the finger 47' of the other 13 arm 47 brought to the front of the finger 30' which is held at its foremost position by the effective magnet 28, and the cam 43 is turned to be in the condition shown in Fig. 6. With this state of affairs it is evi-

dent that the arm 29 is restrained by the finger 46' so that the magnet 27 is thus rendered incapable of effecting the closure of the switch S^2 and consequently prevents the transmission from the signal-key 2 to the signal bell 26. The cam 43 being brought into the indicated position (Fig. 6) thereby closes the switch S^2 ; and during the above operation switch S' remains closed, and switch S^3 remains open to cut out the current from bell 26. With the referred to switches thus disposed, the current passes from battery B through wire f'' through switch S , wires e and o to switch S' and from there by wire m to magnet 42 whence it returns by wire f to battery.

With the opening of the switch-key 1 subsequent to its long initial closure, the magnet 3 is demagnetized with the result that the sector-member 16 is then released from engagement with pinion 15; thus permitting the switch S to open, whereupon the coil 42 is demagnetized and the lever 40 then rises to dislodge the stop 38 thereof from the finger 36' with a consequent movement of the shaft until this finger encounters the stop 39. In such movement of the shaft the cam is turned enough to move the beak 43'' thereof from the position whereat it is shown in Fig. 6 to a second position shown in Fig. 7 with a consequent releasing of the arm 45 which is then influenced by spring 44 to effect the opening of switch S' and the closing of switch S^3 , while switch S^2 is retained closed by the cam. Through closure of switch S^3 , the short taps, which constitute the signals, are free to be transmitted from the signaling instrument to the indicator, or bell, 26, and that, too, without disturbance from the signal of another originating circuit.

Upon the final opening of the switch-key 1 following the completion of the signal the magnet 3 is demagnetized and releasing its angle-lever 3' the spring 10 asserts itself to cause the arm 8 being engaged with the rotating screw to cause the arm finger being thrust below the contact o' of the master-switch S^1 to close the latter. The switch S^2 remains closed, hence a current flows from battery B by wires f'' and d through switch S^1 and continuing by wire e and switch S^2 to wire connections n and m to magnet 42 and returning to battery by wire f . The magnet 42 thereby attracts the armature 41 to cause the lever 40 to withdraw the stop 39 from the finger 36' to release the shaft for rotation and which is arrested by the finger of arm 37 being arrested by the stop 38 whence, through the withdrawal of this stop concurrent with the opening of switch S^2 , the stop 39 is presented to engage the referred to arm and have the various parts which are di-

rectly connected to the shaft occupy their normal positions in which they are represented in Fig. 5.

It may be remarked that the buzzer 50 is operable to give notice of signal calls other than that being transmitted to the indicating bell 26, through the closure of the switch S from any of the originating circuits.

What we claim as our invention, is:

1. A combination with a series of signal circuits and a signal indicating instrument, of means whereby said indicating instrument is made operative for a signal through an extended closure of a signal circuit, said means causing the other of said circuits to be inoperative with respect to said indicating instrument.

2. In combination with a series of signal originating circuits and a signal indicating instrument, of means whereby said indicating instrument is made operative for a signal through an extended closure of a signal originating circuit, said means causing the other of said signal originating circuits to be inoperative with respect to said indicating instrument.

3. In a system of electrical communications, a plurality of signal originating circuits each embracing a magnet and a movable element which is adapted to be influenced by the respective magnet, an electric signal indicating instrument, a secondary circuit embracing said instrument, said secondary circuit being controlled by each of said movable elements, a means actuated by an extended initial action of any one of said signal originating circuits for causing the aforesaid movable elements of the other circuits to become inoperative and non-interfering with respect to a signal being transmitted through the secondary circuit.

4. In a system of electrical communications, a plurality of signal originating circuits each embracing a magnet and a movable element which is influenced thereby, a locking device for each of said movable elements, electrically controlled mechanical means made operative by a preliminary long continued variation of current conditions in any of the signal originating circuits for controlling the actions of the locking devices to cause all of the elements except that which is influenced by the actuating originating circuit to become inoperative.

5. In a system of electrical communication, a cam, means tending to rotate said cam, electrically controlled means for arresting the movements of the cam, circuit closures controlled by the cam, a plurality of electrically operated switches, and means having coincident movements with the cam

and operated by the first named means for causing all but one of said switches to become temporarily inoperative.

6. In a system for transmitting signals, a plurality of circuits, means for closing said circuits, a shaft, mechanical means tending to rotate said shaft, electrically actuated devices for controlling the rotary movements of the shaft, a plurality of 10 electro-magnets in said circuits, each provided with a movable element which is normally arranged to be attracted by the respective magnet, and means carried by the shaft for rendering said movable elements 15 inoperative with respect to the magnets thereof.

7. In a system for the transmission of signals, a plurality of originating circuits, each of said circuits comprising an electro-magnet and a movable element adapted to be influenced thereby and in opposition to a retractile spring, locking devices for the respective movable elements, electrically actuated means made operative by a prolonged 20 preliminary closure of any of the originating circuits and serving to cause said locking devices to become operative except the one which is associated with the movable element for the magnet included in the originating 25 circuit which is affected by a preliminary closure thereof, a signal indicating instrument, a circuit embracing said instrument, and a series of switches which are controlled by the respective elements 30 so that said instrument may be actuated only from the originating circuit which is associated with the operable element.

8. In a system of electrical communication, a shaft, mechanical means, for imparting intermittent rotary movements to the shaft, electrical devices for controlling said means, a cam mounted upon the shaft, circuit closures operated by the cam for governing said electrical devices, a plurality of 40 electro-magnets each provided with a movable element which is normally arranged to be attracted by the respective magnets, and means carried by the shaft for rendering the said movable elements 45 inoperative with respect to the magnets thereof.

9. In a system of electrical communication, a shaft, means tending to impart rotary motion to the shaft, oppositely directed 55 arms provided for the shaft, a controlling electro-magnet, a movable escapement member operated by the magnet whereby each of the arms is engaged twice successively in every rotation of the shaft, a plurality of 60 movable elements, an electro-magnet for each of said elements and arranged to attract the same when the magnet is energized, a retractile spring for each said element to cause the same to be moved away from its

magnet when it becomes demagnetized, and 65 a locking-arm for each said element.

10. In a system of electrical communication, a shaft, means tending to impart rotary motion to the shaft, a cam on said shaft, oppositely directed arms on the shaft, 70 a controlling electro-magnet, a movable escapement member operated by the magnet, whereby each of the arms is engaged a plurality of times successively during every rotation of the shaft, a plurality of movable elements, an electro-magnet for each of said elements and arranged to attract the same when the magnet is energized, a retractile spring for each said element to cause the same to be moved away from 75 its magnet when it becomes demagnetized, a locking arm for each said element operated by said shaft, a circuit closure controlled directly by said cam, a lever actuated by said cam, a signal and a plurality of switches for operating said signal, one of said switches being controlled by said lever and the others by the said movable elements, thereby effecting a closure of circuits in each rotation of the cam. 80

11. In a system of electrical communication, the combination of a series of signal originating circuits each embracing a magnet, a movable element for each of said magnets, a signal indicating instrument, secondary circuits embracing said instrument and individually opened and completed through the medium of the respective said elements, a shaft, means to impart a rotary movement to the shaft, locking devices carried by the shaft for engaging said elements, a magnet, means provided upon the shaft and actuated through the last named magnet for controlling the rotary movements of said shaft to effect the engagement of said 95 locking devices with the movable elements when the latter are in inoperative positions, a circuit embracing the last named magnet, and devices operated from the shaft whereby the last named circuit and said secondary circuits are each completed and opened 100 in the successive rotations of the shaft. 110

12. In a system of electrical communications, a series of signal originating circuits each embracing a magnet, a movable element operated by each of said magnets, secondary circuits controlled by said movable elements, a signal indicating instrument controlled by said secondary circuits, normally inoperative means for engaging said 115 elements to cause them to be inoperative with respect to said magnets, a controlling magnet, a movable member which is actuated by the controlling magnet to regulate the operation of said means, an automatic transmitter provided with electrically actuated parts which are embraced by the respective 120 originating circuits, a third circuit embrac- 125

ing the controlling magnet, a master switch for said third circuit and operated from said transmitter, a fourth circuit embracing said controlling magnet, a normally open closure for the fourth circuit, said transmitter being actuated by a prolonged closure of any of the signal originating circuits whereby the aforesaid means is made opera-

ble to allow the operation of all of the said originating circuits but only the movable 10 element of one of them.
